UNITED STATES PATENT OFFICE

CHARLES H. KESTENMAN, OF PROVIDENCE, RHODE ISLAND, ASSIGNOR TO KESTENMAN BROS. MFG. CO., OF PROVIDENCE, RHODE ISLAND, A CORPORATION OF RHODE ISLAND

METAL BAND OR LINKAGE

Application filed August 4, 1931. Serial No. 555,002.

This invention relates to improvements in flexible metal straps, bands or linkages for use in the manufacture of bracelets, chains, belts and other articles of jewelry or the like.

5 One object of the invention is to provide an improved band or strap of the type specified having closely associated articulated links or chain-elements which are adapted to flex, one in relation to another, in order 10 that the strap or band may be bent into circular form.

Another object of the invention is to provide an improved linkage of the type specified in which the links or chain-elements are 15 more closely and intimately connected to adapt them to be flexed without dislocation of the parts and without revealing unsightly joints or seams.

Another object of the invention is to provide 20 an improved linkage of the type specified having the sides of its links or chain-elements curved or rolled inwardly at the top to overlie and conceal the inner connecting-links with the latter securely held against 25 skewing or displacement.

Another object of the invention is to so form and arrange the links as to simulate the appearance of a cord bracelet as usually constructed of looped bands or cords.

30 Another object of the invention is to provide an improved linkage of the type specified in which the links are proof against breakage or accidental disconnection to render the article in which it is incorporated strong and durable in use.

Another object of the invention is to provide 35 an improved linkage of the type specified which may be manufactured from sheet-metal parts struck up in dies and assembled 40 with a minimum of hand operations, and without the use of solder, screws, pins, rivets or other extraneous parts liable to become loose and cause shakily joints.

45 Further objects of the improvement are set forth in the following specification which de-

scribes a preferred form of construction of the invention, by way of example, as illustrated by the accompanying drawing. In the drawing:

Fig. 1 is a perspective view of the improved 50 metal strap, band or chain showing it bent or flexed in substantially circular form;

Fig. 2 is an enlarged plan view of a series 55 of the links of the strap, band or chain with several of the outer links shown partly in section along their sides to illustrate the arrangement of the inner connecting-links enclosed thereby;

Fig. 3 is an edge view of a series of the 60 links of the strap, band or chain with several of the same shown in section on the line 3-3 of Fig. 2;

Fig. 4 is a cross-sectional view of the linkage taken on line 4-4 of Fig. 2;

Fig. 5 is a perspective view of a partially- 65 formed outer link illustrating the manner in which the inner connecting-links are assembled therewith previous to the final forming of the sides of the outer links; and

Fig. 6 is a perspective view similar to Fig. 5 illustrating the finished form of the outer link with its sides arched or curled inwardly at the top in abutting relationship to permanently connect the inner links therewith.

The present improved linkage, band or chain 70 comprises, in general, a series of box-like outer links having bent-up projections or fingers at their ends, and rectangularly-shaped connecting-links of loop formation interengaged 75 with the fingers on the main links and covered by the sides and top portions thereof. The outer links are constructed with relatively 80 long side-flanges which are bent around in substantially semi-circular form in abutting relationship to form an arched top-closure 85 for the box. The end cross-bars of the inner connecting links are held against the bottom of the box-links by the downwardly folded edges of its side-flanges. In addition to serving 90 as a retaining means for the connecting-

links, the arched top portions of the box-links also enhance the ornamental appearance of the article. Straps, bands or bracelets constructed in accordance with the present 5 invention very closely resemble similar articles made of looped cords of leather, braid, wire mesh or other fabricated material, according to the prevailing mode.

Referring to the drawing, my improved 10 strap, band or chain comprises a series of main elements or outer link-members 2 of box-like form, connected by loop-like inner connecting-links 10, the end cross-bars of which are secured within the main links in 15 the manner as later explained. The box-like outer link-members 2 may be constructed from sheet-metal with a flat bottom or base 4 having side-walls or flanges 5 bent upwardly therefrom at right angles. At each end of 20 the base 4 is an upstanding finger or lug 6 of considerably less length than the side walls. The fingers or lugs 6 serve the purpose of interengaging with the end cross-bars of the connecting-links 10 to be later described. 25 Referring to Fig. 5 of the drawing, the main links 2 may be stamped from sheet-metal stock and bent into the form as illustrated in this view by a single stamping and bending operation performed in dies.

30 The connecting-links 10 may be stamped from sheet-metal stock in the form of rectangular loops with their sides and end-bars of square cross-section. If preferred, however, the connecting-links may be made of either 35 round or square wire bent into a closed loop. With the main links 2 preformed to the shape illustrated in Fig. 5, they are assembled with the connecting-links 10 in the manner as next explained. The connecting-links 10 are 40 looped over the end-fingers or lugs 6 of adjacent box-links 2 as shown in Fig. 5 with their end-bars 11 resting on the base 4 of the main link 2 and their side-bars 12 straddling the fingers. In this arrangement the side-bars 45 12 of the connecting-links fit rather snugly between the side-flanges 5 of the main link 2 and the ends of the fingers 6 to avoid unnecessary side-play therebetween.

50 When the connecting-links 10 have been positioned within the box-link 2 in the manner as above explained the upwardly projecting side-flanges 5 thereof are looped or arched thereover in the manner as illustrated 55 in Fig. 6. It will be observed by reference to this latter view that the side-flanges 5 form a bifurcated top wall for the box with their ends folded inwardly in abutting relationship. The ends of the flanges 5 are thus directed 60 downwardly against the upper edges of the end-fingers 6 to substantially close the ends of the box and retain the end-bars 11 of the connecting-links 10 therewithin. With a pair of connecting-links thus connected to a main link, their projecting ends are placed over 65 the end-fingers 6 of the next adjacent box-

links 2 in the series and secured therein in the manner as above explained. The assembling operation may be continued in this manner until a band or linkage of the required length is formed; or in other cases the intermediate connecting-links may all be placed in connection with a series of box-links as a first step, and thereafter the sides of the box-links may be finally bent or formed into arch-shape by a single operation in a forming die.

70 In order to provide the desired flexibility of the band or bracelet, a slight clearance is allowed between each pair of adjacent connecting-links 10 in the series. It is also to be noted that the end-fingers 6 of the main links 2 project slightly above the top of the connecting-links 10 to provide a clearance whereby the adjacent box-links may be flexed or 75 inclined with respect to each other to permit the bending of the band or bracelet into substantially circular form as shown in Fig. 1. It is desirable, however, to have the clearances slight so that the spacing of the box-links 2 is relatively close to conceal the inner connecting-links 10 from view. The projecting ends of the inner links 10 at the ends of the strap or band may be suitably joined to a clasp or other device for securing the ends together or for attachment to the bails of a 80 wrist-watch.

85 It will be observed from the foregoing that the present improvement provides a particularly neat and simple structure of linkage adapted for use as a strap, band or bracelet, or for incorporation into a girdle, chain or other article of jewelry or adornment. The elements of the linkage being constructed from sheet-metal stampings and formed in dies provide for economy in the cost of manufacture. Moreover, the elimination of pins, 90 rivets, screws and solder makes for easy assembling of the link-elements and therefore further reduces the cost. The arched portions on the top of the main links provide a particularly strong and durable structure and reduce the liability of damage to or dislocation of the parts. At the same time, the improved structure provides for a close association of the links to avoid unsightly joints or 95 seams between the parts.

100 As a further feature of improvement, the arching of the top of the box-links gives the article a more pleasing artistic effect, simulating the appearance of a double-strip metal loop or cord. At the same time it effects an improvement over previously used cord straps or bands in that the article is more 105 sturdy and durable in use without danger of stretching or breaking.

110 While I have herein shown a preferred form of construction of the linkage, it is to be understood that modification may be made 115 in the structure and arrangement of the parts 120

of the device without departing from the spirit or scope of the invention. Therefore, without limiting myself to the exact construction shown, I claim:

- 5 1. A linkage of the type specified comprising substantially box-like link-elements having upstanding sides and lugs at their ends, and connecting-links in looped engagement with the lugs on adjacent box-links and held in connection therewith by the sides of the box-links bent inwardly to form arched portions meeting in a medial plane with their ends abutting the top of the lugs.
- 10 2. A linkage for the purposes specified comprising a series of substantially box-like link-elements each having a bottom, upstanding sides and lugs at its ends, said sides being bent to form arches over the top of the link with their ends adjacent each other and resting upon the top edge of the end-lugs, and connecting-links looped around the lugs on adjacent box-links and held in place by the arched sides thereof.
- 15 3. An improved band or linkage comprising a series of substantially box-like link-elements each having a bottom, upstanding sides, and lugs at its ends, the terminal portions of the sides being arched part way across the top of the link with their edges in turned and adjacent in overlying relation to the top of the end-lugs, and connecting-links looped around the lugs of adjacent box-links and held in connection therewith by the arched sides thereof.
- 20 4. An improved band or linkage comprising a plurality of outer link-elements, each having a bottom, opposite sides and lugs at its ends, the sides of said links being continued in arched portions extending part way across the top of the links with their ends meeting and substantially engaging the top of the end-lugs, and connecting-links looped around the lugs of adjacent outer links to couple them together in substantially abutting relationship with the connecting-links entirely enclosed and concealed within the outer links.
- 25 5. An improved band or linkage comprising a plurality of outer link-elements formed from sheet-metal stock with a bottom, upstanding lugs at the ends thereof and sides bent upwardly from the bottom and curved inwardly in bifurcated contour to form arches overlying the top of the links with their ends adjacent and in close association with the top of the end-lugs, and substantially flat rectangular connecting-links looped around the lugs on adjacent outer links to couple them together in close articulated relationship with said connecting-links enclosed within and concealed by the arched sides of the outer links.
- 30 6. A band or linkage comprising a series of link-elements each having a bottom, upstanding sides, and a lug at its end, the ter-

35 minal portions of the sides being bent to form arches extending part way across the top of the link to form parallel tubular portions simulating a double cord when the links are in connected relationship, and means projecting from the end of each link to engage the lug on an adjacent link to maintain said links in connected relationship, said means being held in engagement with the lugs by the inturned edges of the arched portions of the links abutting thereagainst.

In testimony whereof I hereunto affix my signature.

CHARLES H. KESTENMAN.
